ORNAMENTAL METAL-WORK PANEL

Wendall E. Brown, Fort Worth, Tex., assignor to McKinley Iron Works, Fort Worth, Tex., a partnership

Application May 23, 1957, Serial No. 46,303

Term of patent 14 years

(Cl. D54—2)

Fig. 1 is a side elevation of an ornamental metal-work panel embodying my new design;

Fig. 2 is an edge view of the same;

Fig. 3 is a sectional view taken on line 3—3 in Fig. 1.

I claim:

The ornamental design for an ornamental metal-work panel, as shown.
